US00D984285S

(12) **United States Design Patent** (10) **Patent No.:** **US D984,285 S**
(45) **Date of Patent:** ** *Apr. 25, 2023

(54) **WATCH DISPLAY STAND**

(71) Applicant: **Andre G. Lavoie**, San Francisco, CA
(US)

(72) Inventor: **Andre G. Lavoie**, San Francisco, CA
(US)

(*) Notice: This patent is subject to a terminal disclaimer.

(**) Term: **15 Years**

(21) Appl. No.: **35/510,655**

(22) Filed: **Apr. 27, 2020**

(80) **Hague Agreement Data**

Int. Filing Date: **Apr. 27, 2020**

Int. Reg. No.: **DM/208965**

Int. Reg. Date: **Apr. 27, 2020**

Int. Reg. Pub. Date: **Oct. 30, 2020**

(57) **CLAIM**

The ornamental design for a watch display stand, as shown and described.

DESCRIPTION

1.-3. Watch display stand

FIG. 1.1 Front view

FIG. 1.2 Back view

FIG. 1.3 Right view

FIG. 1.4 Top view

FIG. 1.5 Bottom view

FIG. 1.6 Perspective view

(Continued)

The broken line showing of the watch display stand is for the purpose of illustrating environment and forms no part of the claimed design.

1 Claim, 6 Drawing Sheets
